UNITED STATES PATENT OFFICE.

JOHN J. SEEMAN, OF BARSTOW, CALIFORNIA, ASSIGNOR OF ONE-HALF TO
LOUIS E. PORTER, OF BARSTOW, CALIFORNIA.

CHAIN WRENCH.

SPECIFICATION forming part of Letters Patent No. 710,719, dated October 7, 1902.

Application filed August 27, 1901. Serial No. 73,498. (No model.)

To all whom it may concern:

Be it known that I, JOHN J. SEEMAN, a citizen of the United States, residing at Barstow, in the county of San Bernardino, State of California, have invented new and useful Improvements in Chain Wrenches, of which the following is a specification.

My invention relates to that class of wrenches wherein one end of a chain is connected to a suitable handle, and the chain is employed to pass around the pipe to be turned and the free end to be then fastened to the handle, the chain and handle coöperating to turn the pipe; and the objects thereof are to provide a wrench of simple construction, in which the adjustment of the chain can be readily effected, and which will quickly and securely grip the pipe without the danger of slipping; and which can be used equally well with either side of the wrench upward, and which is adapted to grasp and hold pipes of standard sizes or irregular sizes, equally well. I accomplish these objects by the wrench described herein and illustrated in the accompanying drawings, in which—

Figure 1 is a side view of my wrench in place on a pipe. Fig. 2 is a plan of my wrench removed from the pipe.

In the drawings, A is the handle, having a head B, to which the chain C is attached pivotally, so that the free end of the link attached to the head will swing over the end of and to either side of the head. Back of the head is a transverse opening D through the handle, which lies in the same plane as the pivot which unites the chain to the head, through which the chain may render freely in adjusting the chain on the pipe. This opening is contracted toward the head, so that a link of the chain will pass edgewise into the contracted portion; but the junction of two links will not render therethrough, thereby enabling the chain to be adjusted as to length at every link, which enables me to use a single wrench on many different sizes of pipe.

In the operation of my wrench the chain is first passed under and over the pipe and the free end passed through the opening in the handle and is preferably adjusted as to length so that when the chain is taut the head of the handle will be a little above the center of the

pipe, as shown in Fig. 1. Now when a downward force is applied to the rear of the handle the greater the pressure the tighter the chain grips the pipe. As the handle is alike on both sides and as the chain will turn to either side of the head, it makes no difference which side is turned upward. By putting the chain over the pipe, then passing it down and under and adjusting it through the opening in the handle, an upward force may be applied to turn the pipe. Any shape may be given to the opening through the handle, providing it is contracted toward the shorter end or head of the handle, and the links of the chain are of such shape that they will render freely through the enlarged portion of the opening in the handle and will pass into and be prevented from rendering through the contracted portion of the opening in the handle.

The chain must be pivotally attached to the head at such a distance from the front or face of the head that when the wrench is placed on the pipe the face of the head will contact with the pipe a little above the diameter of the pipe, which lies in a plane parallel with the plane which passes longitudinally through the handle, and prevent the first link of the chain from contacting with the pipe, as shown in Fig. 1.

Having described my invention, what I claim as new, and desire to secure by Letters Patent, is—

A chain wrench comprising a handle having a head; an opening through the handle back of and near to the head; said opening having a contracted portion toward the head; and a chain pivotally connected to the head intermediate the face thereof and the opening in the handle and having the link connected to the head, adapted to swing over the face of the head to either side thereof, said pivotal connection lying in the same plane as the opening through the handle and being a sufficient distance from the face (of the head) to prevent the first link of the chain from coming in contact with the pipe when the wrench is used thereon with the head thereof in contact with the pipe above the diameter of the pipe, which lies in a plane parallel with the plane which passes longitudinally through the handle; the free end

of said chain being adapted to render freely through the enlarged portion of the opening in the handle and to pass into the contracted portion when adjusted on the pipe and to be held from rendering through such contracted portion of the opening.

In witness that I claim the foregoing I have

hereunto subseribed my name this 22d day of August, 1901.

JOHN J. SEEMAN.
